UNITED STATES PATENT OFFICE

GERHARD MORRIS BECHTEL, OF ALLENTOWN, PENNSYLVANIA

ROTARY DRIER

Application filed May 13, 1929. Serial No. 362,683.

This invention relates to driers of the revolving drum type in which the material to be treated is fed into one end of an inclined rotating cylinder or drum and discharged from the other end, and in its travel the material being treated is subjected to a current of hot air passing in a direction opposite to that in which the material is traveling.

10 In driers of this type the elongated cylindrical shell revolves about its longitudinal axis in one continuous rotating motion and the direction may be either clockwise or counter clockwise. The feed end of the 15 drier is slightly raised to a higher elevation than the discharge end and during the rotation thereof the material travels from the high towards the low end. Through this cylinder from the lower towards the upper 20 end is directed a current of heated air which travels with a velocity equal to the draft produced by the stack or exhaust fan located at the other end of the cylinder. During this operation a very small portion only of 25 the material to be dried contacts the heated gases, the greater portion of the gases passing through the drier shell without contacting the material to be dried.

A primary object of this invention is to 30 overcome these objectional features and provide means whereby the heated air or gases are checked in their flow through the drier shell and brought into direct contact with the material to be treated causing a thorough 35 commingling of the gases or heated air with the material to be dried.

Another object of the invention is to provide an apparatus whereby the heated gases 40 are held in direct contact with the material being dried for a maximum length of time thereby producing a complete and thorough drying of the material with a minimum consumption of fuel.

45 Another object of the invention is to provide a drying cylinder with means whereby the heated air or gases is caused to pass in a zig-zag path through the cylinder whereby the gases are contacted with the material 50 a number of times and for longer periods,

thereby insuring the complete drying of the material with high efficiency.

Another object of the invention is to so construct a drying shell that the baffle plates for the gases perform the double function of agitators for the material whereby it is commingled and thoroughly exposed to the drying action of a heated air current.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a top plan view of a rotary drier constructed in accordance with this invention shown in connection with the furnace for supplying heat thereto and a portion of the storage bins in which the material to be treated is located;

Fig. 2 is a longitudinal section thereof with the feed hopper and exhaust hood shown in side elevation;

Fig. 3 is a transverse section of the drier cylinder taken on the line 3-3 of Fig. 2;

Fig. 4 is a similar view taken on the line 4-4 of Fig. 2;

Fig. 5 is a transverse section through the drier drum or cylinder showing on an enlarged scale one of the combined baffles and agitators constituting a part of this invention;

Fig. 6 is a similar view taken through the furnace;

Fig. 7 is an enlarged detail longitudinal section showing of the deflectors or baffles in side elevation; and

Fig. 8 is a detail perspective view of one of the agitator blades forming a part of the baffle;

Fig. 9 is an enlarged detail section of the self-adjusting connection taken on the line 9-9 of Fig. 5.

In the embodiment illustrated an ordinary furnace is used such as is employed in apparatus of this character and which is here indicated by the numeral 1. This furnace 1 has a pit 2 located at one end thereof which is designed to receive the dried material 100

after it has passed through the drying cylinder or drum 10 which discharges at its lower end thereinto, said cylinder being open at this end to permit the free passage of the heat currents from the furnace through the cylinder.

This drum or cylinder 10 may be mounted and rotated in any suitable manner well known to those familiar with this art it being here shown in the form of a large hollow cylinder preferably constructed of steel plates securely riveted together along their longitudinal and circumferential seams and is of a diameter and length to suit the capacity required. This cylinder 10 is surrounded by two bearing rings 11 and 12 known in the art as steel tires which are mounted so as to ride on suitable supports constructed so as to render the rotation of the cylinder as free and frictionless as possible. The supports 13 and 14 here shown are provided with the necessary bearing shafts and rollers on which the tires ride while the drier is being rotated, the upper or rear end support being considerably higher than the front support so as to insure the proper inclination of the cylinder. These supports 13 and 14 may be mounted on any suitable foundation, concrete blocks or pillows 15 and 16 being here shown for this purpose.

A ring gear 17 also surrounds the drum 10 and meshes with a drive pinion 18 carried on a counter shaft 19 which in turn is driven by means of a belt pulley 20 which is here shown driven by a motor 21.

The higher rear end of the drum 10 is also open and has opening thereinto a feed pipe 22 which leads from a feed hopper 23. This feed pipe controls the flow of material from the bin or hopper to the drier by means of a suitable gate not shown and which is so set to cause the flow of material to the drier to be uniform. An exhaust hood 24 engages the drier cylinder 10 at its high end and may be connected to an exhaust fan or to a stack. This exhaust hood 24 is provided with an opening in the top to connect to an exhaust fan and is also equipped with an opening to receive the feed pipe 22.

Located within the drier cylinder or shell 10 are two series of baffle plates or deflectors 25 those of one series being located on a side diametrically opposite to those of the other series and the deflectors of the two series are arranged in staggered or alternated relation as is shown clearly in Fig. 2. These deflectors or baffles 25 are made in sections and all exactly alike and hence one only will be described in detail. One of these baffle plates is shown on an enlarged scale in Fig. 5 and comprises two side plates 26 and 27, a center plate 30 and two expansion angle members 35 and 36 which latter connect the center plate with the side plates by means of bolt and slot connections to provide and take

care of expansion and contraction in the deflector which is incident to the changing temperature within the drier. This slot and bolt connection of these plates or sections provides a self-adjusting connection between them which prevents buckling of the deflector and distorting of the drier shell and avoids all passage of gas between the sections and also the entanglement of the material therewith.

The side plates 26 and 27 are secured to the shell 10 by means of angle iron riveted to the plates and to the shell by counter sunk rivets so as to avoid the heads of the rivets wearing off and thereby loosening the plates. These connecting angle irons are numbered 28 in Fig. 5.

The center plate 30 is fastened to the shell 10 by angle irons 31 in the same manner as are fastened the side plates. Fixed to the side and center plates and to the shell 10 and extending at right angles therefrom are a plurality of agitating plates 32 any desired number of which may be employed five being here shown which are connected with the plates and with the shell by means of angle irons riveted thereto, the heads of said rivets preferably being counter-sunk. The expansion angles 35 and 36 are securely riveted to the center plate 30 to form a firm and rigid connection between them. The same legs of these angles are provided with a suitable number of slotted openings 33 and through which pass bolts 33a which connects the angles with the side plates and thus provide for expansion and contraction between the center and side plates.

These deflectors or baffles 25 perform the double function of baffles or deflectors for the heated gases which pass through the drier or cylinder from the furnace 1, and the blade 32 thereof as agitators for the material.

The deflectors 25 are fastened to the inner face of the drier shell at any desired angle and as above described those of one series are arranged to alternate with those of the other so that the gases entering at the lower end of the cylinder from the furnace pass through the shell and contact first with one deflector and then with another which causes them to be deflected and carried into direct contact with the material which is passing through the cylinder from the higher rear end and which is being changed from one side to the other incident to the rotation of the cylinder. The changing of the direction of the gases by the baffles from a straight or direct flow to a direction at right angles causes them to be thoroughly mixed with the material being dried thereby. It is, of course, understood that the longer the period of time that the heating gases are held in contact with the material to be dried the more thoroughly will be the effect of the

gases on the material and which will consequently reduce the amount of fuel consumed in order to produce the same effect.

The arrangement of the deflectors causes them to balance the rotating of the drier and not in any way injure the uniformity of the rotation which would otherwise be produced.

As shown in Fig. 6 the deflectors 25 are arranged in staggered relation around the periphery of the drum or cylinder on its inner face, each succeeding deflector being offset at 45° from the preceding baffle or deflector in reference to the circumference of the circle of the cylinder. Eight of the baffles are shown and are numbered 25, 25a, 25b, 25c, 25d, 25e, 25f, and 25g. It will thus be seen that by so arranging these deflectors they are all set opposite one another for each 45° in a circle which balances and maintains uniformity of rotation in addition to multiplying the number of times the heated gases are deflected towards the bottom of the drier shell thereby bringing the gases into contact with the material a number of times and for long periods increasing the drying qualities and efficiency of the drier. It will be obvious that this arrangement of the deflectors completely baffles the passage of the heat currents and prevents them from passing in a straight line through the drum.

The deflector or baffle plates 25 equipped with agitating blades operate first to deflect the heated gases passing at these points and cause the material, which is being constantly lifted by the agitating blades, to mix more thoroughly with the gases and consequently create a more thorough drying process and increase the efficiency of the drier considerably. Secondly, the purpose of these elements is to increase the efficiency of the drier by reducing the cross sectional area of the drier to one-half whereby the velocity of the heated gases is considerably increased and thereby carries out the suddenly accumulated moisture which is driven from the material to be dried by means of the baffle plates or deflector plates and their agitating blades. These two conditions always exist and their combination greatly improves the efficiency of the drier.

The blades or plates 32 also operate as agitators for the material being dried by lifting the material from the bottom of the drier shell and carrying it to a position of 45° above the horizontal center line. When in this position the material will slide off the plates 32 directly in front of the deflectors which is the hottest zone, and the material passing through this zone will be more effectively dried. The material, as it drops from the top to the bottom of the drier, is entirely surrounded by hot gases which produce a thorough drying effect. Owing to the fact that the agitating plates 32 are secured to the drier shell and to the deflector this op-

eration is repeated at each deflector and insures a more thorough drying of the material. The plates 25 constructed as herein described will cut through the material to be dried like a knife and have no openings such as would catch the material and impede its flow through the cylinder. 70

It will thus be seen that the material is fed slowly by the rotation of the cylinder 10 from one end thereof being constantly agitated by the blades 32 of the baffles or deflectors and when it reaches the lower end of said cylinder it will be thoroughly dried and cured and will be discharged into the pit 2 from which it may be conducted by a 80 suitable conveyor not shown.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed. 90

I claim:

1. In a rotary drier, a rotatable cylinder having an inlet and an outlet, a baffle extending radially from one wall of the cylinder for a portion of the diameter thereof, said baffle being composed of a plurality of adjustably connected sections to provide for the expansion and contraction and having means to prevent the passage of air between the sections. 100

2. In a rotary drier, a rotatable cylinder open at both ends and having baffles extending radially from opposed walls of the cylinder for a portion of the diameter thereof, said baffles being provided with means to facilitate the baffling of the air current passing through the cylinder and means to operate as agitators for the material being treated. 105

3. In a rotary drier, a rotatable cylinder open at both ends and having baffles extending radially from opposed walls of the cylinder for a portion of the diameter thereof, said baffles being provided with means to facilitate the baffling of the air current passing through the cylinder and to operate as agitators for the material being treated, each of said baffles being composed of a plurality of adjustably connected sections to provide for expansion and contraction. 115

4. In a rotary drier, a rotatable cylinder open at both ends and having baffles extending radially from opposed walls of the cylinder for a portion of the diameter thereof, said baffles being provided with means to facilitate the baffling of the air current passing through the cylinder and to operate as agitators for the material being treated, each of said baffles being composed of a plurality of connected sections, the connectors between 125

the sections being in the form of angle irons fixed to one section and having a bolt and slot connection with an adjacent section.

5. A rotary drier including a rotatable cylinder provided on its inner face with a plurality of inwardly extending baffle plates, each of said plates being composed of a plurality of adjustably connected sections with combined baffle and agitator blades attached to said sections and to the cylinder.
